UNITED STATES PATENT OFFICE.

EDWARD A. BUELL, OF DEKALB, ILLINOIS, ASSIGNOR TO SELECTIVE SIGNAL & TELEPHONE MANUFACTURING CO., OF SYCAMORE, ILLINOIS, A CORPORATION OF ILLINOIS.

ELECTROMAGNETIC MECHANISM.

SPECIFICATION forming part of Letters Patent No. 792,692, dated June 20, 1905.

Original application filed May 2, 1904, Serial No. 205,876. Divided and this application filed August 9, 1904. Serial No. 220,118.

To all whom it may concern:

Be it known that I, EDWARD A. BUELL, a citizen of Canada, residing at Dekalb, in the county of Dekalb and State of Illinois, have 5 invented a certain new and useful Improvement in Electromagnetic Mechanism, (being a division of my application, Serial No. 205,876, filed May 2, 1904,) of which the following is a full, clear, concise, and exact description, reference being had to the accompanying drawings, forming a part of this specification.

My invention relates to electromagnetic apparatus, and is of particular service in the operation of switching mechanism. In practicing my invention I impart to the armature of a single electromagnetic organization a greater number of motions than have been imparted to the same hitherto.

In the preferred embodiment of the invention a pivotally-mounted armature is employed whose pivot is adapted for bodily movement by the armature, about which the armature not only rotates, but is adapted for complete bodily movement therewith.

25 In practicing my invention I employ a centrally-pivoted armature which is adapted to oscillate or rotate in opposite directions, and which is adapted for movement with its pivot.

In the preferred organization there is employed 30 an electromagnet having two core branches, each desirably supporting or carrying a helix, said core elements being preferably upon the same side of the armature that is common thereto. The mounting for the pivot is desirably confined to straight-line 35 travel by having a plunger-and-socket guiding action, though I do not wish to be limited to any very peculiar characteristics of construction that have entered into the preferred embodiment of the invention.

The device of my invention is of particular service in the operation of the selective-signal-controlling apparatus at the substations of a party telephone-line, it having been of 45 special utility in setting, locking, and releasing an associated circuit-controlling wheel,

the armature in moving in one direction serving to set the wheel, when moving in another direction serving to lock the wheel, so that wheels at other stations can be moved without disturbing the adjusted position, and serving to release its associated wheel to restore the apparatus at this substation to normal conditions when subscribers are through with their conversation. I have therefore shown the particular adaptation of my invention to use in connection with party telephone-lines; but I do not wish to be restricted to any particular use that the device of my invention may be put.

I will explain my invention more particularly by reference to the accompanying drawings, in which—

Figure 1 illustrates a party telephone-line and so much of an apparatus at an exchange 65 as is necessary to an understanding of my invention. Fig. 2 is a front view showing the relation of the coils and armature. Fig. 3 is a view on line *aa* of Fig. 1 of the electromagnetic portion of the structure.

Like parts are indicated by similar characters of reference throughout the different figures.

In order that the specific application that I make of my present invention may thoroughly 75 be understood, I will first describe in detail the telephone system to which it has been applied.

At the exchange I have indicated line-jacks 1 and 2 of normally independent telephone-lines, there being a cord connecting apparatus for uniting independent telephone-lines in conversation, such cord connecting apparatus including an answering-plug 3 and a connecting-plug 4, which cord-circuit has the usual 85 associate apparatus, including, among other things, (not shown,) an operator's telephone outfit 5, an operator's ringing-generator 6, a listening-key 7, and a ringing-key 8, there being provided a common actuating-lever 9, 90 whereby the springs of the listening-key may be pressed against the operator's telephone-

terminals and whereby the springs of the ringing-key may be removed from their normal contacts and brought into engagement with the alternate contacts which constitute 5 the ultimate terminals of the ringing-generator 6. Both of the alternate contacts of the ringing-key 8 are thus used when the bells to be rung by the generator are in metallic connection only with the telephone-lines.

10 I have indicated grounded signal receivers or bells 10 at the substations, which are connected with the sleeve side of the party telephone-line 11, and I hence preferably provide a supplemental key 12, which is operated to 15 limit the current emanating from the generator to the sleeve side of the telephone-line, the circuit being completed by way of the grounded alternate contact of the key 12 and the grounded bells. I, however, do not wish 20 to be limited in all embodiments of my invention to the use of the grounded bells. I have indicated upon the party telephone-line three stations A, B, and C, though the number of stations connected with the line may 25 be varied. The various stations are connected in multiple or bridge between the sides of the party-line, station A being included in such a bridge 13 14, while station B has a bridge-path 15 16, while station C has a bridge-path 17 18. I prefer the bridge arrangement, as the element of impedance is so largely removed, though I do not wish to be limited to such an arrangement. The apparatus at station B is illustrated in detail. The apparatus 30 of the other stations is preferably similar thereto. At station B, I have illustrated as one type of substation outfit a gravity telephone switch-hook 19, a telephone-receiver 20 to be supported thereby, and a transmitter 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910

current to be diverted from the circuit containing the line-indicator through the bell to have the same operated at the calling-station, said bell being in shunt relation with the generator.

Either or both of the branches 15 and 16 70 may be subject to the electrical control had by the device of my invention. I have shown both sides 15 and 16 to depend for their continuity upon a movable circuit-changer 24, desirably in the form of a ratchet-wheel, said 75 ratchet-wheel carrying or operating two contact elements, each mechanically subdivided into two parts 25 and 26 and 25' and 26' insulated therefrom, the parts of each set of elements being desirably constructed in two 80 mechanically-separated but electrically-connected elements which preferably are in the form of pins, though I do not wish to be limited to a contact element of this form. When the ratchet-wheel is in its initial or normal 85 position, the elements 25 and 25' are in electrical connection with riders 27 27', which in turn are connected with and constitute parts of conductors 15 and 16. The elements 25 26 and 25' 26' are separated by distance corresponding to distances between varying numbers of teeth at the different stations. The pins 25 and 25' at each station are what might be termed the "normal" or "zero" contact elements. The normal or zero elements 25 and 25' 95 at each station are those contact elements which are always directly engaged by the riders 27 27' at all of the stations when the line is idle, which engagement is to be maintained when the line is to be used as an ordinary party-line. The elements 26 26' may be termed the "alternate" contact elements and are those elements which are directly engaged with the riders 27 27' at any selected station when secrecy is desired and where selected signaling is to be practiced.

In placing two subscribers on the same line in secret connection the operator intermittently actuates the electromagnetic apparatus, to be hereinafter described, for the purpose of shifting the circuit-changer 24 until the proper elements 26 26' (which, as hitherto set forth, are located differing distances away from the elements 25 25', according to the different stations) are brought into direct engagement 115 with the riders 27 27' at the stations between which the secret connection is to be established. For example, station B indicates the second station upon the line, station C may indicate the third station, and station A the 120 first. At station A the pins 25 25' and 26 26' preferably have no tooth intervening. At station B the pins 25 25' and 26 26' have one tooth intervening, and at station C the pins 25 25' and 26 26' have two teeth intervening. 125 To connect station B with station C, for example, the operator shifts the circuit-changer 24 two steps and then locks the same by

mechanism to be set forth and shifts the circuit-changer 24 at station C another step, the said latter circuit-changer having previously been operated two steps in setting the apparatus at station B. It will be apparent to those skilled in the art that at all other stations the riders 27 27' are not in connection with those portions of the circuit changers or wheels 24 that are electrically connected with the teeth 25 25' and 26 26', thereby opening the branches that depend for their continuity upon the engagement of the riders 27 27' with one or the other of the teeth 25 25' and 26 26'. Thus both terminals of the telephone-receivers are disconnected from the line by being included in open circuit.

Having described one form of circuit-changing apparatus that may be employed in connection with my invention for governing the association of the subscribers' stations with the party-line, I will now describe my improved electromagnetic mechanism that is employed for effecting the operation of the said circuit-changers and will thereafter describe the switching apparatus at the exchange that is employed for operating the electromagnetic mechanism.

The wheels 24 are provided with coil-springs 28, by which when released by my magnetic actuating mechanism they are restored to initial positions, where the contacts 25 25' engage the riders 27 27', the wheel 24 at station B having thereon an arm 29, engaging a stop 30 to limit the return of the wheel. My improved electromagnetic mechanism has two spools or helices 31 32, preferably unprovided with a magnetic yoke, but having a common armature 33 centrally pivoted between the poles of the spools. The magnet of this mechanism is provided with a permanent magnet 34 to induce polarities of the same sign in the poles of the coils 31 32 that are presented to the armature 33 and to also polarize said armature. One of the windings, as the winding 31, when included in circuit with the source of direct current tends to reinforce or increase the field at the pole of said winding 31 opposed to the armature 33, while the other winding is reversely wound to secure an opposite effect. By proper circuit connections the armature 33 may be caused to oscillate in a clockwise direction or in a counter-clockwise direction, as desired, or the armature may be bodily moved toward both opposing poles. The pivot for the armature is desirably provided upon a plunger 34', that has splined engagement with a housing 35, the parts 34' and 35 being desirably of non-magnetic metal. The pivot is preferably subdivided into two parts 36 37, the bracket 38, carried by the plunger 34', serving to support these pivots, the parts of the bracket that immediately support the pivots being preferably of ear-like formation, the armature 33 being

interposed between these ears. Some suitable means may be provided for normally maintaining the armature away from both poles. I have indicated retractile springs 39 and adjustable back-stops 40, against which the armature is normally held by said retractile springs. The work to be performed by this electromagnetic mechanism may be accomplished by some suitable extension of the armature—as, for example, the rod or lever 41, projecting at right angles to the armature. I consider the electromagnetic mechanism just described to be broadly new with me, irrespective of what it is adapted to. In the present instance this electromagnetic mechanism has been applied to the peculiar form of secrecy and cut-out switching mechanism that has been hitherto described. The first function that this mechanism has to perform is the movement of the circuit-changing wheel 24 from engagement with its normal stop 30, to which end the armature 33 is attracted toward both of the magnet-poles opposing the same. This movement causes the dog 42, pivotally supported upon the arm 41, to advance the ratchet-wheel against the force of the coil-spring 28. The next function of the magnetic mechanism is to lock the circuit-changing wheel 24 in the selected position. This is accomplished by causing a rotation of the free end of the arm 41 downwardly by the counter-clockwise movement of the armature, so that the cam 44 may be pressed against the plunger 45 against the force of a coil-spring 46, whereby a pin 47, carried upon the wheel, may be forced into engagement with the hooked end of the plunger 45, which desirably is sufficiently yielding, so as to permit the said hooked end to pass the pin 47, but which is of such a nature as to secure a locking engagement until the engagement between the pin and plunger has been broken. As the dog 42 moves the wheel in a counter-clockwise direction, the locking-pawl or dog 48, having a fixed axis of rotation at its rear end, prevents the return of the wheel, which locking-pawl is pivoted upon a link 49, that may be moved back and forth in an inclined groove 50 in an enlarged end of the arm 41. It will be seen how effectively the two elements 48 and 45 serve to define the position of the wheel 24, the first preventing movement by the spring and the second, when set, preventing movement of the arm 41 and the armature 33 in a direction parallel to the cores of the magnet. It will be understood that the plunger 45 need only be operated at the station where the circuit-wheel 24 is to be moved the lesser number of times in effecting telephonic communication between that station and another where the circuit-wheel is to be moved a greater number of times. Such movement of the circuit-wheels, as is understood, is only to be had when secrecy is desired, so that the subscribers

may call each other or the exchange without the aid of my improved electromagnetic mechanism. When it is desired to release a given circuit-wheel, the armature 33 is moved in a clockwise direction, whereby the dog 48 is lifted, permitting the spring 28 to move the wheel 24 back against its stop 30. When this movement occurs, the plunger 45 is free from the pin 47, whereupon the spring 46 restores said plunger to its initial or normal position. The various operations of the magnetic circuit-controlling mechanism at each station may be governed by a battery 51, divided into two parts for some purposes, but all of which are used for the purpose of effecting the bodily reciprocation of the armature 33. The extreme poles of this battery are connected with the alternate contacts of the selecting-key 52, the springs whereof are thrust against said alternate contacts when selection at the sub-stations is to be effected. The lever of the key 52 is preferably maintained toward the right, while the wedge end of the lever 9 is moved to and fro to intermittently effect the connection of the springs of the key 8 with their alternate contacts that are in electrical connection with the springs of the key 52, whereby the battery 51 is intermittently in bridge of the party-line for the purpose specified.

I have found by experiment that one-half of each battery will not be sufficient to effect bodily reciprocation of the armature 33, but will effect the operative energization of one coil of the magnet only. The left-hand end of the battery 51 is preferably employed for operatively energizing the coils 31 32 independently, depending upon the direction that the current from this portion of the battery is impressed upon said windings, such current being insufficient to operatively energize both windings in a manner to effect the bodily reciprocation of the armature 33, but sufficiently increasing the magnetization at one of the poles opposed to the armature 33 and weakening the other to secure the oscillation of said armature in one direction or the other, according to the direction of the current. The poles of this half of the battery are connected with the springs of the key 53 when said springs are thrust against their alternate contacts that are connected with said poles, the plunger 54 being employed for effecting this movement of said springs. Current from the left half of the battery 51 is thereupon caused to flow over the line in a direction to reinforce the magnetization of the core of the winding 32 and to oppose or weaken the magnetization of the core of the winding 31, whereupon the armature 33 is rocked in a counter-clockwise direction to effect a depression of the plunger 45 into engagement with the pin 47. When it is desired to restore the individual mechanisms to

their initial positions at the substations, the locking-key 53 is released and the springs of the releasing-key 55 are spread apart by their associate lever, whereupon the left-hand half of the battery 51 has its connection with the line reversed, causing a reversal of the conditions just described respecting the energization of the cores of the windings 31 32, forcing the armature 33 to turn in a clockwise direction and thereupon elevate the dog 48 to permit the spring 28 to restore each circuit-wheel against its stop 30.

While I have herein particularly set forth one adaptation of my improved electromagnetic magnetism, I do not wish to be limited thereto, nor do I wish to be limited to the precise details of construction set forth, as changes may be made without departing from the spirit of my invention; but,

Having thus described my invention, I claim as new, and desire to secure by Letters Patent, the following:

1. An electromagnetic mechanism having a swinging armature that may swing under the influence of the magnetic element, and a mounting for the armature that is free to move with the armature through the influence of the magnetic element whereby the said armature may be bodily moved, substantially as described.

2. A circuit-changing mechanism including an electromagnet having a circuit-controlling armature adapted to be oscillated and also to be bodily moved by the field of the magnet, substantially as described.

3. An electromagnetic mechanism having a swinging armature that may swing under the influence of the magnetic element, and a mounting for the armature that is free to move with the armature through the influence of the magnetic element whereby the said armature may be bodily moved, the said electromagnetic element presenting two poles to the armature, one pole serving to effect movement of the armature in one direction, the other pole serving to effect movement of the armature in another direction, while both poles serve, in conjunction, to effect bodily movement of the armature, substantially as described.

4. An electromagnetic mechanism having a swinging armature which is also bodily movable, said electromagnetic element presenting two poles to the armature, one for moving the armature in one direction, the other for moving the armature in another direction, the two poles, when acting in conjunction, serving to effect bodily movement of the armature, substantially as described.

5. An electromagnet comprising two helices, an armature pivoted between the helices, a bodily-movable mounting for the armature, and spring mechanism acting upon said mounting normally maintaining the armature away from said helices, substantially as described.

6. An electromagnetic mechanism possess-

ing two helices, a bodily-movable armature presented to the said helices, and spring mechanism acting upon the armature, normally maintaining the armature away from said helices but permitting the said armature to be moved in one direction by one helix and in another direction by the other helix, in addition to the bodily movement of the armature by the

action of both helices thereupon, substantially as described.

In witness whereof I hereunto subscribe my name this 23d day of July, A. D. 1904.

EDWARD A. BUELL.
